UNITED STATES PATENT OFFICE.

JOHN WILLIAM WRAY, OF LONDON, ENGLAND, ASSIGNOR TO INTERNATIONAL COMBUSTION ENGINEERING CORPORATION, OF NEW YORK, N. Y., A CORPORATION OF DELAWARE.

CHAIN GRATE.

Application filed March 12, 1927, Serial No. 174,937, and in Great Britain November 6, 1925.

This invention relates to travelling grates of the endless chain type.

It is the primary object of my invention to provide a chain grate of such character that the finer particles of fuel are not lost by sifting through air spaces of the grate, but are held on the surface thereof and burned as the grate moves through the combustion chamber.

10 A further object of my invention lies in the provision of means for catching and retaining such small fuel and dust as may happen to fall through the air spaces and discharging it at the end of the grate.

15 A further object lies in the provision of means for dislodging and discharging any clinkers which may adhere to the grate.

Another object of my invention is the provision of a grate wherein the grate bars are pivoted to carriers and lie one against the 20 other in the upper run of the grate but fall away and travel free of each other in the lower run.

25 A further object is the provision of means for mounting the grate bars which permit of ready removal and replacement of any of the grate bars or groups thereof.

These, together with such other objects as may hereinafter appear, or are incident to my invention, I obtain by means of a construction which I have illustrated in preferred form in the accompanying drawings, 30 wherein—

Fig. 1 is a fragmentary longitudinal section of a portion of the grate showing diagrammatically the rear drum towards which the upper run of the grate travels and is taken substantially on the line 1—1 of Fig. 3.

Fig. 2 is a longitudinal section similar to Fig. 1 showing a portion of the upper run of the grate, some of the grate bars being shown in elevation and others in section.

Fig. 3 is a transverse section of the grate with the grate bars appearing in elevation, the right hand half being taken on the line 3—3 of Fig. 1, and the left hand end being taken on the line 3^a—3^a of Fig. 1.

Fig. 4 is a plan view of a portion of the grate with certain of the parts omitted for the sake of clarity.

Figs. 5 and 6 are detail views showing a modification.

Fig. 7 is a diagrammatic view showing the

relation of the grate to the drum and supports.

Referring now to Figs. 1 and 4, it will be seen that I have shown a grate comprising two sets of grate bars 5. Generally the width of the grate is such that a bar extending the whole of the width would be too heavy and according to the invention there may be several bars in the width, carried by a series of chains in number normally one or more than the number of bars in the width of the grate.

In the construction shown in Figs. 1 to 4 the grate bar 5 has a pivot 6 at each end which engages in a cavity 7 in a grate bar carrier or side casting 8. The side castings 8 are secured to carrying links 10 of the chain A by means of bolts 9. The links 10 are connected by means of smaller links 10^a thus forming an endless chain of alternate carrying and connecting links.

The links 10 also carry the spindles 21 encircled by the sleeves 20. Rollers 12 are mounted on the sleeves 20 and the chain is supported by these rollers which run on suitable supports 11 (see Fig. 2 and Fig. 7) and over the drum 13.

The preferred shape of the grate bars 5 will be appreciated from the drawings. In the upper run of the chain they rest against each other at an angle of about 45°, the downward slope being in the direction of travel. Suitable projections 18 prevent actual contact through the whole of the length of the bar, affording an air space between bars.

The pockets 19, formed by turning up the lower edge of the bar 5, receive any fine fuel or dust which may fall through the air spaces and such fine material is discharged as the grate bars reverse their position in travelling over the drum 13, as will be seen in Fig. 1.

As the chain A leaves the upper run of the grate the bars turn on their pivots discharging the ash and any material collected in the pockets 19. This movement of the grate bars also dislodges any clinkers which may have been formed and such clinkers are also discharged.

Figs. 4 and 5 illustrate a modified form of side casting which instead of having a number of cavities 7 has a single continuous

slot 15. In this construction the pivot of each grate bar 5' has a collar 16, the diameter of which is such that there will be a little play between bars. Except for this collar 5 the bar is otherwise the same as the bar 5 shown in Figs. 1 to 4.

An opening 17 into the slot 15 permits the pivots being slid successively into or out of the slot. It will be understood that in 10 order to do this, the casting must be tilted out of its normal position to clear the connecting links 10° enough to permit the pivots to be slid in between the lower surface of the casting and the connecting link. This 15 clearance is not sufficient in normal operation to permit accidental disengagement of a pivot.

Owing to the louvre-like formation of the grate it will be seen that the most of the fine 20 fuel will remain on the surface of the grate instead of falling through the air spaces between bars and that any material which does fall through will be caught and discharged at the end of the grate.

25 I claim:—

1. A travelling grate of the endless chain type having a plurality of cooperating endless chains, grate bar carriers mounted on said chains, transversely extending grate bars pivoted at each end to one of said carriers, each grate bar having a general upward and forward slope when in fuel supporting position, and also having a pocket opening upward at its rearward lower edge 35 when in such position.

2. A travelling grate of the endless chain type having an endless chain construction, grate bar carriers carried by the endless chain construction, a plurality of trans-

versely extending grate bars pivoted to 40 each carrier, the bars on each carrier lying one against the other and one bar on each carrier lying against a bar of an adjacent carrier in the upper run of the grate, all of the bars hanging free in the lower run of 45 the grate.

3. A travelling grate of the endless chain type having a plurality of cooperating chains, grate bar carriers carried by each of said chains and a group of grate bars 50 everyone of which has one end pivoted on a single carrier of one chain and the other end pivoted on a single carrier of an adjacent chain.

4. A travelling grate of the endless chain 55 type having a plurality of cooperating endless chains, grate bar carriers mounted on said chains, transversely extending grate bars pivoted at each end to one end of said carriers, each grate bar lying in a sloping 60 position in the upper run of the grate and also having a pocket at its lower edge adapted to catch small fuel and dust when in such position.

5. A travelling grate of the endless chain 65 type having a plurality of cooperating endless chains, grate bar carriers mounted on said chains, transversely extending substantially flat grate bars pivoted at each end to one of said carriers and lying in a sloping 70 position in the upper run of the grate and each grate bar having a pocket at its lower edge adapted to catch small fuel and dust when in such position.

In testimony whereof I have hereunto 75 signed my name.

JOHN WILLIAM WRAY.

Certificate of Correction.

Patent No. 1,649,557.

Granted November 15, 1927, to
JOHN WILLIAM WRAY.

It is hereby certified that error appears in the printed specification of the above-numbered patent requiring correction as follows: Page 2, line 59, claim 4, strike out the word "end," second occurrence; and that the said Letters Patent should be read with this correction therein that the same may conform to the record of the case in the Patent Office.

Signed and sealed this 13th day of December, A. D. 1927.

[**SEAL.**]

M. J. MOORE,
Acting Commissioner of Patents.
